UNITED STATES PATENT OFFICE.

CHARLES WILLIAM ALLEN, OF DEER PARK, ONTARIO, CANADA.

DESIGN FOR A STOVE.

SPECIFICATION forming part of Design No. 16,937, dated October 12, 1886.

Application filed August 19, 1886. Serial No. 911,353. Term of patent 7 years. Patented in Canada August 3, 1886, Design No. 4.

To all whom it may concern:

Be it known that I, CHARLES WILLIAM ALLEN, residing at Deer Park, in the county of York and Province of Ontario, in the Dominion of Canada, journalist, have invented and produced a new and original Design for Stoves, of which the following is a specification, reference being had to the accompanying photograph, forming part thereof.

10 Heretofore the top of every base-burner stove has been surmounted by an urn, pot, ball, statuette, or fanciful ornament, while the rest of the ornamentation has been floral or fanciful, but not corresponding with the particular device or ornament on the top, as before mentioned.

15 The leading feature of my design is that the decoration of all the more important parts is harmoniously representative of the arms and armor carried and worn by knights and their retainers during the period commonly referred to as the "days of chivalry." Thus the ornament on top of stove is a knight's helmet and

20 armored bust, A. The handle by which feeder-lid may be displaced represents a sword-hilt, 25 C. At the corners of top are halberds D. The panels bear representations of various kinds of ancient arms—viz., crossed battle-axes and maces F, daggers G, and lances H. The foot-rests are spears, I. Prominent in front is a 30 knight's shield, E.

I claim—

The design for stoves herein shown and described, the same consisting of a stove having the configuration and ornamentation representing a knight's helmet and armored bust, A, a sword, C, halberds D D D D, a shield, E, crossed maces and battle-axes F F F F, daggers G G G G G G G G, lances H H H H, and spears I I.
